(57) CLAIM

The ornamental design for a smoking accessories tray set, as shown and described.

DESCRIPTION

FIG. 1 is a front perspective view of a smoking accessories tray set, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top view showing the smoking accessories tray set, in configuration of use; and,

FIG. 9 is a front view showing the smoking accessories tray set, in another configuration of use.

All the broken lines in the drawings depict portions of the smoking accessories tray set that form no part of the claimed design.
